UNITED STATES PATENT OFFICE.

WALTER P. WIENS, OF PEORIA, ILLINOIS.

INTERNAL-COMBUSTION ENGINE.

Application filed November 3, 1924. Serial No. 747,448.

This invention relates to internal combustion engines. An object of the invention is the provision of an engine of this type wherein due to the construction employed 5 all noises incident to its operation will be reduced to the lowest possible point.

Another object is to produce an engine of the internal combustion type having a cylinder of a tapered form adapted to rotate 10 within a correspondingly formed seat in the engine-block and provided with ports to be brought into register with inlet and exhaust ports in said block.

Still another object is the provision of 15 means by which the rotating cylinder may be kept lubricated in a very efficient manner.

Other advantages will be brought out in 20 the following specification aided by the accompanying drawings wherein:

Figure 1 is a side elevation of an engine involving my invention, parts of which are shown in section.

Figure 2 is a vertical transverse section 25 of part of the engine showing a cylinder rotating gearing.

Figure 3 is a horizontal section of a rotating cylinder and part of the engine block showing intake and exhaust ports.

Figure 4 is an elevation of part of a cylinder and worm gearing for driving it.

Figure 5 is an elevation of part of one of the cylinders of my invention.

Figure 6 is a transverse section of the same.

Figure 7 is a plan of a packing ring.

Figure 8 is a side elevation of part of a cylinder and a vertical section of part of the cylinder block, and

Figure 9 is a vertical section of a part of 40 a cylinder and an attached ring employed in rotating it.

It is my purpose to make use of a tapered cylinder rotatable in a tapered seat in the engine block arranged in such manner that,

45 while free to rotate, gas leaks will be prevented and perfect lubrication maintained. Further, my purpose is to impart rotation to the cylinder through a timing gear system of worm and worm wheels operated

50 from the crank shaft. The structures described are used with the whole purpose of furnishing an engine totally devoid of noises incident to engine operation besides producing an engine vastly more efficient.

55 In the drawings, 1 designates the engine

block and 2 the cylinder head. The block is provided with a series of tapering bores 3 corresponding to the number of cylinders to be employed and these are water jacketed in the customary manner as shown. The 60 bores are smallest at the lower or crank case side of the block and each receives into it a cylinder 4 correspondingly tapered and which is provided centrally with a cylindrical bore 5 extending entirely through it. 65 The upper surface of the cylinder is preferably flush with the surface of the block 1 and may have a working fit against the under side of the head 2. Preferably the latter has a depending cylindrical extension 6 70 adapted to fit into the bore 5 and has a packing ring 7 seated in its periphery to lie against the wall of said bore 5.

A portion of the upper end of the cylinder is formed with a head 8 through which 75 extends an inlet port 9, and an exhaust port 10 which during rotation of the cylinder are adapted to separately register in proper timing with passages 11 and 12 respectively of the said block 1, these passages being 80 shown in Figure 3. Seated in a groove at each side of the ports is a packing ring 14. The grooves are indicated at 13 in Figure 8 and each varies in width and the rings are made to correspond therewith.

85 That is to say, preferably each ring instead of having a uniform width throughout as ordinarily used is made much wider at one side than at the other as clearly shown in Figure 5 to seat in a groove of like form. 90 The purpose of this is that since the cylinder rotates the edges of the ring and of the grooves in being inclined at an angle to the plane of rotation will travel over a wide path without likelihood of scoring the surface of the block 1. Preferably a stud 14' 95 on the inner surface of each ring is made to seat in a recess 14² in the bottom of the groove, Figure 8, so that the ring and cylinder will rotate together or as a unit.

100 The portion of the cylinder below the head 8 is preferably provided with a spirally formed groove 15, Figure 2, and a resultant spiral edge 16 is inclined to the plane of rotation and cannot therefore score the tapered seat in the block but must move over a wide path and acting as though the surface of the cylinder were unbroken by such groove. The advantage of this construction 105 is that friction is somewhat reduced since 110

the groove 15 is designed to contain a lubricant to be supplied thereto by some such means as will be described presently.

The lower end of the cylinder depends 5 below the engine block and its seat and is furnished within the crank case with an annular flange 17 which may be attached in any suitable manner after the cylinder has been placed in its seat.

10 The relation of the flange to the extremity of the cylinder may be as shown in Figure 9 and the upper or top surface of said flange is furnished with a series of teeth 18 in the form of conical pins, for example, to mesh 15 with a driving worm 19 on a timing shaft 20 supported in suitable bearings 21, but one of which is shown, Figure 2, this being a well known expedient. One of the shafts 20 is shown at each side of the cylinder in said 20 Figure 2, there being a pair of worms 19 for each cylinder of the series employed thus providing for a most positive and even drive of the cylinders with no tendency to tilt or bind.

25 The crank shaft is designated at 21 and this carries a worm 22, for example, with which meshes at opposite sides a worm-wheel 23 on each of two shafts 24 mounted in suitable bearings 25 on a convenient part 30 of the engine structure. These shafts diverge and each carries at its upper or opposite end a worm 26 having driving engagement with a worm-wheel 27 on one of the shafts 20, as clearly shown in Figures 1 and 2, and it is 35 required, of course, that the worms and worm-wheels of the system shall be of such relation that the speed of rotation of the cylinders shall present the intake and exhaust ports 9 and 10 to the respective passages 11 and 12 of the cylinder-block in proper timing 40 with respect to piston travel.

At 28, Figure 1, is designated an oil pump which withdraws oil from the crank case 29 through a suction pipe 30 and distributes it 45 to the top of each cylinder through a system of piping 31. Figures 2, 3 and 8 will make the matter of lubrication clear. In Figure 8, for example, a passage 32 is created in the cylinder-block and one of the pipes of the 50 system 31 is connected into the outer terminal of such passage, the opposite terminal of the latter opening into the top of the bore 5 so that the oil may be delivered at the top of the rotating cylinder in a recess 32' created by beveling the top edge of the cylinder 55 at 32° from which position the oil may work downwardly. There is a vertical "bleeder" passage 33 created in the cylinder, Figures 2 and 3, also, through which the oil may pass 60 down into the spiral groove 15 to finally enter the crank case. The direction of rotation of the cylinder may be such that the tendency of the spirally arranged contacting faces 16 will be to work the oil upwardly. 65 The cylinder bore is lubricated, of course,

in the usual manner, i. e., the splash system. The packing ring 7 in the cylinder-head-extension prevents oil entering the combustion chamber and aids, as well, in holding compression.

The worms 19 overlie the flanges 17 of the cylinders in order that any tendency of the latter to unseat in the slightest degree will be met, the teeth 18 being of such construction as will permit free action of the worms.

The construction provided in my improved engine is such that there can be no attendant noises during operation since the only reciprocating parts are the pistons. The timing gearing is of a wholly noiseless type and the cylinder rotation, noiseless in itself, affects the registration of the inlet and exhaust passages.

The tapered form of cylinder freely admits of such expansion and contraction as might naturally result, and reasonable wear is easily taken care of since the cylinder can move further down into its seat. After long wear, however, said cylinder may be replaced by another.

I claim:

1. An internal combustion engine including in its construction an engine block having a tapered bore constituting a seat for a cylinder, including ports leading into said bore, and a tapered cylinder adapted to have a working fit upon the walls in said seat, said cylinder having a cylindrical bore, the walls of said cylinder having ports therein to register with those of the block.

2. An internal combustion engine including in its construction an engine block having a tapered bore, a cylinder tapered throughout its length fitting said bore, the block and cylinder including ports adapted to register, said cylinder having a cylindrical bore into which the ports open, and means to rotate the said cylinder.

3. An internal combustion engine including in its construction an engine block having a tapered bore extending therethrough, that portion of the bore having the smallest diameter terminating at and opening into the crank case of the engine, a cylinder head overlying and closing the large end of the bore, a cylinder tapered throughout its length adapted to fit in said bore and having a part depending into the said crank case, and means within the latter to engage and rotate the cylinder.

4. An internal combustion engine block including a bore tapering from the upper side of the same toward its lower side, said block having ports in its top portion communicating with the said bore, and an externally tapered, bored cylinder adapted to seat in the tapered bore of the engine block and having ports in its walls communicating with its own bore adapted to register with the ports of said block.

5. An internal combustion engine including an engine block having a tapered bore whose greatest diameter is at the upper portion of said block, a tapered cylinder seated 5 in the bore adapted to rotate therein and having a bore, a cylinder-head closing the bore and adapted for holding the said cylinder in its seat, the block and said cylinder having ports adapted to register during the 10 rotation of the latter.
6. An internal combustion engine including in its construction an engine block having a tapered bore extending therethrough, that portion of the bore having the smallest 15 diameter terminating at and opening into the crank case of the engine, a cylinder head overlying and closing the large end of the bore, a cylinder tapered throughout its length adapted to fit in said bore throughout 20 the same and having a part depending into the said crank case, and means within the latter to engage and rotate the cylinder.
7. An internal combustion engine including in its construction an engine block having 25 a bore of tapered form extending through it, a cylinder head, a cylinder having a corresponding taper adapted to seat in said bore and means adapted to rotate the cylinder and for assisting in holding it in its seat.
8. An internal combustion engine including in its construction an engine block having a tapered bore whose smallest diameter is at the crank case side of said block, a cylinder 30 of a corresponding taper seated therein having a central bore, a cylinder head overlying the cylinder and having a depending extension fitting into the last named bore, a packing ring disposed between the extension 35 of the head and the cylinder, and means to
- rotate the cylinder and for assisting in holding it in its seat in said tapered bore.
9. An internal combustion engine including in its construction a cylinder block having a bore decreasing in diameter from its 45 top side toward its crank-case side, a cylinder of a corresponding taper seated therein having a central bore, there being ports in the block opening into its bore, there also being ports in the cylinder to register with 50 the first named ports, a packing ring interposed between the cylinder and said block at each side of the ports, there being a spirally arranged groove in the surface of the cylinder facing the wall of the tapered bore for 55 containing a lubricant.
10. An internal combustion engine including in its construction an engine block having a tapered bore, a cone shaped cylinder adapted to seat therein, there being a spiral 60 groove in the periphery of the cylinder for receiving a lubricant, there also being a passage in the cylinder leading from its top into said groove, and means for forcing a lubricant from the crank case of the engine 65 into the top of the said tapered bore of the block.
11. An internal combustion engine including in its construction an engine block having a tapered bore smallest at the crank case 70 side of said block, a tapered cylinder seated therein adapted to rotate and having a central bore for a piston, said cylinder having a peripheral groove in its wall adjacent the wall of the bore of the block of containing 75 a lubricant, and means by which to supply the groove with such lubricant.

In testimony whereof I affix my signature.

WALTER P. WIENS.
